UNITED STATES PATENT OFFICE.

NORMAN NEWTON HILL, OF EAST HAMPTON, CONNECTICUT.

BELL.

SPECIFICATION forming part of Letters Patent No. 445,370, dated January 27, 1891.

Application filed September 29, 1890. Serial No. 366,508. (No model.)

To all whom it may concern:

Be it known that I, NORMAN NEWTON HILL, of East Hampton, in the county of Middlesex and State of Connecticut, have invented new 5 Improvements in Bells; and I do hereby declare the following, when taken in connection with the accompanying drawings and the letters of reference marked thereon, to be a full, clear, and exact description of the same, and 10 which said drawings constitute part of this specification, and represent, in—

Figure 1, a view in side elevation of a bell constructed in accordance with my invention, and Fig. 2 a view thereof in central longitudinal section.

15 My invention relates to an improvement in that class of bells in which two bells placed mouth to mouth are attached to one end of a handle. Heretofore bells of this class have 20 generally been made by attaching them directly to a wire at suitable distances apart and driving the same into the handle or by placing a piece of tubing between them and then passing a wire or a nail or a screw through 25 both bells, the tubing, and into or through the handle.

30 The object of my invention is to improve upon such constructions and to produce a simple, cheap, and strong bell of finer tone than the bells heretofore made.

35 With these ends in view my invention consists in the combination, with a handle having a spindle forming a continuation of one of its ends, of two bells placed mouth to mouth and one being driven over the said spindle and the other being seated upon the outer end thereof, means for securing the bell last mentioned to the spindle, and a jingle. 40

My invention further consists in certain 45 details of construction and combinations of parts, as will be hereinafter described, and pointed out in the claims.

As herein shown, the handle A of the device has a spindle B made integral with and 50 forming an extension of one of its ends, the base of the spindle being provided with an enlargement C, merging at its inner end into a shoulder D, located where the spindle meets the handle. If desired, the spindle may be 55 made independently of the handle and con-

nected therewith, so as to form an extension thereof. The two bells E E' are placed mouth to mouth, the inner bell E having a sufficiently large opening E² formed in it to adapt it to pass over the end of the spindle, 55 after which it is crowded down over the enlargement C thereof and held in place solely by the shoulder D and by the friction of the metal edge E³, which was displaced in forming the opening E², with the surface of the 60 said enlargement. If desired, however, the said enlargement may be dispensed with and the spindle made of uniform diameter. The outer bell E' is seated upon the end of the spindle and secured thereto by a screw F, 65 passing through a small opening formed in it and into the spindle. As herein shown, the outer end of the spindle is capped by a light ferrule G to strengthen the device and prevent the spindle from splitting; but such ferrule is not essential and may be dispensed with; nor do I limit myself to the use of a screw for securing the outer bell in place, as I may use a wire or a nail in its stead. The 70 usual jingle J is placed between the two 75 bells when they are being assembled.

By employing a spindle forming an extension of the handle for carrying the bells and holding them properly apart I secure a very simple and strong construction, particularly 80 when, as I prefer, the spindle is made integral with the handle. Furthermore, by forming a larger opening in one bell than in the other they are caused to sound in different tones with all the pleasing effect of a chime. 85

In view of the modifications herein suggested I do not limit myself to the exact construction herein shown and described, but hold myself at liberty to make such changes and alterations therefrom as fairly fall within 90 my invention.

Having fully described my invention, what I claim as new, and desire to secure by Letters Patent, is—

1. In a bell, the combination, with a handle 95 having a spindle forming an extension of one of its ends, of two bells placed mouth to mouth and one being driven over the said spindle and the other being seated upon the outer end thereof, means for securing the last - men- 100

tioned bell to the end of the spindle, and a jingle interposed between the two bells, substantially as described.

2. In a bell, the combination, with a handle having a spindle made integral with one of its ends and a shoulder where the same meets it, of two bells placed mouth to mouth and one being driven over the said spindle and against the said shoulder and the other being seated upon the outer end of the spindle,

means for securing the bell last mentioned to the spindle, and a jingle, substantially as described.

In testimony whereof I have signed this specification in the presence of two subscr- 15
ing witnesses.

NORMAN NEWTON HILL.
